Attorney

UNITED STATES PATENT OFFICE.

RALPH R. ROUSH, OF COLUMBUS, OHIO.

TOOTHBRAHSH.

Application filed April 29, 1921. Serial No. 465,455.

To all whom it may concern:

Be it known that RALPH R. ROUSH, a citizen of the United States, residing at Columbus, in the county of Franklin and State of Ohio, has invented certain new and useful Improvements in Toothbrushes, of which the following is a specification.

This invention relates to an improved tooth brush, wherein improved features of 10 design and construction are present which are employed in a mechanical sense for the purpose of enabling the operator or user thereof to manipulate the brush to advantage when engaged in the operation of cleaning teeth, in order that the bristles of the brush will be enabled to not only brush the anterior surfaces of the teeth but to be also capable of being used to advantage in properly reaching, without discomfort or inconvenience to the operator, the posterior surfaces of the teeth, and thus providing a structure whereby the teeth may be properly cleansed over all exposed surfaces thereof so that the same may be maintained in a 25 thoroughly cleansed and sanitary condition.

The present invention aims particularly to provide a tooth brush which will constitute an improvement over the tooth brush of present conventional form and usage. As 30 is well known, the ordinary tooth brush may be employed with facility when utilized in removing extraneous matter from the anterior surface of the teeth, but are not capable of being used to advantage when the 35 rear or inner surfaces of the teeth are being cleaned, therefore, by reason of this fact tartar or other destructive film accumulates on the rear surfaces of the teeth and exercises injurious effects thereon. The present 40 invention consists in the provision of a brush wherein the handle portion terminates in an angularly disposed head, from which the bristles project in a direction substantially at right angles to the handle of the brush, 45 the lower surface of the bristles being angularly disposed with respect to the head, whereby by virtue of these features of construction, the brush will be capable of being easily and properly positioned so as to engage all of the exterior surfaces of the teeth, 50 permitting thereby of a thorough and efficient cleansing thereof, not only as regards their exterior surfaces, but also the interior surfaces.

For a further understanding of the inven-

tion reference is to be had to the following description, and to the accompanying drawing, in which;

Figure 1 is a side elevation of the improved tooth brush comprising the present 60 invention, and illustrating the use thereof, and

Figure 2 is a perspective view of the brush.

Referring more particularly to the details 65 of construction involved in the specific embodiment of the invention disclosed in the drawing, the numeral 1 designates the brush in its entirety. The brush, in this instance, is formed to include a longitudinally extending handle 2, which may be of any suitable proportions and formed from desired materials, one end of the handle terminating in an outwardly curved slightly enlarged portion 3 which is of such formation as to 70 enable the same to be readily adapted to the palm of the operator's hand and to be prevented from slipping therefrom during active operation.

The opposite end of the handle 2 terminates 80 in an offset or angularly out-turned enlarged head 4, which is integrally formed with a handle 2 and is so designed that the same may be readily received without discomfort within the mouth. The head 4 consists of a 85 curved outwardly enlarging section 5, which is adapted to unite the handle 2 with the bristle receiving enlargement 6 provided upon the outer portion of the head, and bristles 7 are arranged to project from the 90 substantially flat and oval surface 8 provided upon the enlargement 6, the said bristles extending in a plane substantially parallel with the longitudinal axis of the head 4, and at right angles substantially to the handle 2, 95 the head 5 serving to space the bristles appreciably from the handle. It will be observed that the bristles are terminated in such manner that the same will produce an angularly disposed brushing surface 9, the 100 shorter bristles of which being disposed toward the handle 2, while the longer bristles are situated at the extreme outer edge of the head 4.

It will be apparent from the foregoing 105 that the present invention produces a tooth brush which by reason of the presence of the out-turned head 4 and the bristles 7 thereof, will enable the user thereof to dexterously wield the brush so that the surface 9 may be 110

positively, conveniently and easily brought into positive engagement with all tooth surfaces, and in such an effective manner as to enable the brush to positively remove all 5 extraneous matter from the teeth. The surface 9 causes the brush to be used with a vertical up and down motion, or in other words when being employed the bristles of the brush are being moved away from the 10 gums and not toward the latter thus preventing the brush from injuring the gums or to cause any receding thereof. In this respect it may be noted that if the brush were to be used so that the bristles thereof would tend 15 to be moved upwardly or downwardly toward the gums, the longer bristles, by being situated at the outer end of the head, will

tend to bend over, thus preventing further brushing action and injury to the gums.

What is claimed is:

20 A tooth brush comprising a handle and a brush head, the brush head having a shank the axis of which projects from the plane of the back thereof substantially at right angles thereto and a handle bent from the outer extremity of said shank in a broad curve lying in a plane substantially parallel to the plane of the back, and a brush on the front of said head having substantially the whole of its brushing surface inclined to the plane of the 25 face of the brush head and toward the handle.

25 In testimony whereof I affix my signature.
30 RALPH R. ROUSH.
